United States Patent Office

Des. 183,373
Patented Aug. 12, 1958

183,373

PANEL OF PLASTIC SHEET MATERIAL OR SIMILAR ARTICLE

Arno H. Scheiding, Rowayton, Conn., assignor to L. E.
Carpenter & Company, Inc., Wharton, N. J., a corpo-
ration of New Jersey

Application November 27, 1957, Serial No. 48,688

Term of patent 14 years

(Cl. D87—3)

Fig. 1.

Fig. 2.

Fig. 3.

Fig. 1 is a plan view of a full panel of plastic sheet material embodying the new design taken on a reduced scale;

Fig. 2 is a view of a portion of Fig. 1 within the solid line frame II of that figure on a full scale; and

Fig. 3 is a sectional view taken along the line III—III of Fig. 2, illustrating the contours of the embossed ridges and grooves in the plastic sheet material.

I claim:

The ornamental design for a panel of plastic sheet material or similar article, substantially as shown.
